CLAIM

The ornamental design for a detergent tablet, shown and described.

DESCRIPTION

FIG. 1 is a perspective view of the detergent tablet of our design;

FIG. 2 is a front and rear elevation view thereof;

FIG. 3 is a left and right side elevation view thereof;

FIG. 4 is a top and bottom plan view thereof;

FIG. 5 is a perspective view of a second embodiment of the detergent tablet of our design;

FIG. 6 is a front and rear elevation view thereof;

FIG. 7 is a left and right side elevation view thereof;

FIG. 8 is a top and bottom plan view thereof;

FIG. 9 is a perspective view of a third embodiment of the detergent tablet of our design;

FIG. 10 is a front and rear elevation view thereof;

FIG. 11 is a left and right side elevation view thereof; and,

FIG. 12 is a top and bottom plan view thereof.
